UNITED STATES PATENT OFFICE

131,630

DESIGN FOR A TEXTILE FABRIC

Alice Klinke, New York, N. Y., assignor to Electro-Technical Products, Inc., Nutley, N. J., a corporation of New Jersey

Application July 1, 1941, Serial No. 101,838

Term of patent 3½ years

To all whom it may concern:

Be it known that I, Alice Klinke, a citizen of the United States, residing at #434 Lafayette Street, New York city, in the county of New York and State of New York, have invented a new, original, and ornamental Design for a Textile Fabric, of which the following is a specification, reference being had to the accompanying drawing, forming part thereof.

The figure is a plan view of a piece of textile fabric showing my new design, a unit of which is contained between the dot and dash lines, the same being repeated in regular succession as indicated by the extension beyond the unit boundaries.

I claim:

The ornamental design for a textile fabric, as shown and described.

ALICE KLINKE.
